Patented May 28, 1912.

UNITED STATES PATENT OFFICE.

EDWIN GUTHRIE, OF WASHINGTON, DISTRICT OF COLUMBIA.

ENGINE-STARTER.

1,027,648.

Specification of Letters Patent.

Patented May 28, 1912.

Application filed March 1, 1912. Serial No. 680,913.

To all whom it may concern:

Be it known that I, EDWIN GUTHRIE, a citizen of the United States, residing at Washington, in the District of Columbia, have invented certain new and useful Improvements in Engine-Starters, of which the following is a specification.

This invention relates to engine starters, and belongs to that class of devices intended to rotate the shaft of a gas engine to set the engine in motion, without employing the usual hand crank.

The object of this invention is to provide, in connection with a tank for the storage of gas under pressure, a ventilating fan having parts of special arrangement and construction and carrying peripheral buckets, upon which the stored gas, directed by adjacent jet nozzles, may be impelled to revolve the fan, and the engine shaft, with which the fan is operatively connected.

The accompanying drawings illustrate the preferred method of carrying out this invention.

Figure 1 shows the rear side of a radiator with this invention applied, and sets forth the connection between the fan and the shaft of the engine. Fig. 2 represents the vertical section of a cylinder of a gas engine, and shows the connection between the cylinder and storage tank for collecting the gas under pressure, and in this figure likewise appear the plurality of check-valves employed in the connecting tube. Fig. 3 is a top plan view of the engine, and a portion of the frame of a motor vehicle, and shows this invention in proper position with respect to the various parts concerned. Fig. 4 is a top view, looking into the curved side of the jets segment.

Throughout the drawings and description, the same letter refers to the same part.

The frame A of the vehicle carries the engine B having engine shaft b, which may be rotated by the customary hand crank C.

In rear of the radiator D is the fan E supported by a bearing bracket e attached to the engine bed. The fan, which is intentionally constructed stout enough for the service expected of it, is provided with a peripheral ring F having spaced buckets f, best shown in Fig. 1. The scale of drawing in that figure is slightly enlarged, and, the size of the buckets somewhat exaggerated with reference to the size of the fan, for the purpose of rendering the illustration plainer.

A sprocket wheel G secured to the fan shaft, is connected by chain g with the sprocket H secured on the engine shaft b.

The engine may have one or more cylinders J and j, connected by the tube K with a storage tank k, and including more than one check valve L and M. One check-valve is usually located near the engine, and the other near the tank. The object in having more than one check-valve is to lessen the vibration of the body of gas stored in the tank by the repeated explosions in the upper part of the cylinder, with which tube K is shown to be connected in Fig. 2.

Considering Figs. 1, 2, and 3, the tube m is shown. It leads from the tank k to the plug valve N, which has an operating lever n pivotally coupled by connecting rod O with the bell crank P. The other leg of the bell crank is connected with the draw rod Q leading to any convenient point, and by which the plug valve may be turned. The turning of the valve N admits stored gas into the hollow jets segment R, that is constructed with a number of jet nozzles r directed toward the buckets f on the periphery of the fan. The gas stored being very hot, it is advantageous that the storage tank shall be supported at some point below the frame where air may freely flow over it when the vehicle is in motion. If the engine will not start "on spark", the rod Q is actuated and the contents of tank k, in whole or in part, are discharged against the buckets f. There are a number of jet nozzles, in order that the impact and reaction of the gas may affect a number of the buckets at the same time, and, taking into consideration the leverage available by reason of the diameter of the fan, considerable turning power is exerted.

Having now described this invention, and explained the mode of its operation, what I claim is:—

1. In an engine starter, the combination with an engine having an engine shaft, of a revoluble fan arranged to cause air to flow over the engine to cool the same, the said fan having a series of buckets, means constructed to transmit the movement of the engine shaft to the fan and the movement of the fan to the engine shaft, a fluid storage tank, a member having jet nozzles directed toward the buckets of the fan, and tubular connections including a cut-off valve and arranged between the tank and said member.
2. In an engine starter, the combination

with an engine having an engine shaft, of a radiator, a revoluble fan arranged between the engine and radiator and constructed to cause air to flow over the engine and through the radiator to cool the same, the said fan having a series of buckets, means constructed to transmit the movement of the engine shaft to the fan and the movement of the fan to the engine shaft, a fluid storage tank, a member having jet nozzles directed toward the buckets of the fan, and tubular connections including a cut-off valve and arranged between the tank and said member.

3. In an engine starter, the combination with an engine having an engine shaft, of a revoluble fan arranged to cause air to flow over the engine to cool the same, means con-

structed to transmit the movement of the engine shaft to the fan and the movement of the fan to the engine shaft, a fluid storage tank, a member having jet nozzles directed toward the fan, the said fan being constructed to be revolved by impinging fluid jets from said member, and tubular connections including a cut-off valve and extending between the said storage tank and the said member.

In testimony whereof I affix my signature in presence of two witnesses.

EDWIN GUTHRIE.
